LAMP BASE

Edward L. Wheat, Darien, Conn.

Application November 14, 1952, Serial No. 22,277

Term of patent 14 years

(Cl. D48—20)

To all whom it may concern:

Be it known that I, Edward L. Wheat, a citizen of the United States, residing at Darien, county of Fairfield, and State of Connecticut, have invented a new, original, and ornamental Design for a Lamp Base, of which the following is a specification, reference being had to the accompanying drawing, forming part thereof.

Fig. 1 is a front elevational view of a lamp base, showing my new design.

Fig. 2 is a side elevational view thereof.

Fig. 3 is a plan view thereof.

I claim:

The ornamental design for a lamp base, as shown.

EDWARD L. WHEAT.
